UNITED STATES PATENT OFFICE.

WILLIAM H. CURRIER, OF BRAINTREE, MASSACHUSETTS.

SEWING-MACHINE.

SPECIFICATION forming part of Letters Patent No. 580,849, dated April 20, 1897.

Application filed November 6, 1896. Serial No. 611,194. (No model.)

To all whom it may concern:

Be it known that I, WILLIAM H. CURRIER, a citizen of the United States, residing at South Braintree, in the county of Norfolk and State 5 of Massachusetts, have invented certain new and useful Improvements in Sewing-Machines; and I do hereby declare the following to be a full, clear, and exact description of the invention, such as will enable others skilled 10 in the art to which it appertains to make and use the same.

The present invention relates to lock-stitch sewing-machines, and more particularly to that class of lock-stitch machines embodying 15 a circular needle and reciprocating shuttle.

The object of the present invention is to provide a simple and effective means for holding the shuttle-thread within the path of movement of the needle, when the shuttle is 20 in its retracted position, to prevent a twist or knot in the lock as the stitch is formed; and to this end the present invention consists of the devices and combination of devices hereinafter set forth and claimed.

25 The present invention is shown in the accompanying drawings, in which—

Figure 1 shows a portion of the head of a lock-stitch welt-machine embodying the invention. Fig. 2 shows an enlarged detail 30 view of the shuttle box or race and portions of the mechanism for actuating the shuttle. Fig. 3 is a similar view showing a modified form of the present invention.

Similar letters of reference refer to similar 35 parts throughout the several views.

Referring to the drawings, A represents the back-rest; B, the looper; C, the needle; c, the needle-segment; D, the take-up; d, the take-up lever; E, the thread finger or meas- 40 ure; F, the thread-retainer, which retains the loop of needle-thread while the shuttle is passing through the same, and G the loop-spreader, which spreads the loop while held by the retainer for the passage of the shuttle, all of which parts, except as hereinafter noted, together with their actuating mechanism, may be of any usual or convenient construction and form no part of the present invention.

45 As shown in the drawings, the parts above referred to are substantially similar in form and arrangement to corresponding parts of

the machine now known in the trade as the "Goodyear lock-stitch welt-machine" and embodying the invention of Christian Dancel. 55

The shuttle is shown at H and is arranged to reciprocate in the inclined shuttle box or race I, being actuated therein by suitable mechanism, which may be and conveniently is substantially similar to that in said Good- 60 year machine.

In accordance with the present invention the shuttle-race I is provided with a thread-guide, which receives the shuttle-thread as the shuttle is retracted and supports the same 65 within the path of motion of the needle—that is, within the circle which would be formed by the rotation of the needle on its segment center.

The thread-guide above referred to, as 70 shown in Figs. 1 and 2, consists of the angularly-bent rod or finger i, one end of which is secured to the shuttle-race I upon one side of and adjacent to the rear of the shuttle and which extends vertically and laterally, (to- 75 ward the front of the machine), and the forward end of which is secured to the front portion of the shuttle-race. The position of the angularly-bent rod or finger i is such that as the shuttle falls it receives and retains the 80 shuttle-thread and supports it within the path of motion of the needle. It will be noted that the laterally or forwardly extending portion of the rod or finger i is arranged at such an angle that the thread will not slip off of said 85 finger.

As shown in Fig. 3, the thread-guide consists of a shoulder i², formed upon the shuttle box or race I, the upper edge of the shoulder i² being arranged to receive and support 90 the thread substantially in the manner in which the same is supported upon the angular rod or finger i, as hereinbefore described.

The operation of the machine of the drawings, in so far as the same is material to the 95 present invention, is described as follows: The shuttle being in its retracted position, and the thread being held by the thread-guide within the path of motion of the needle, the needle draws up a loop of thread outside 100 of the shuttle-thread or, as shown in the drawings, under said thread, which loop is taken from the needle by the thread-retainer, and while the loop is still closed the shuttle moves

upward from its retracted position to a position above the loop, passing outside of the loop. The loop is then opened by the spreader, and the shuttle returns to its retracted position, 5 passing through the loop and carrying its thread through the same, after which the stitch is set in the usual manner.

It will be noted in connection with the foregoing that if the shuttle-thread is allowed to fall outside of the path of motion of the needle before the needle brings up the loop the lock-stitch will be formed with a twist 10 in the shuttle-thread or supply-thread, which will prevent said threads from properly rendering about each other to position the lock 15 in the material; but as provided with my improved thread-guide the shuttle-thread is always held within the path of motion of the needle while the loop is being brought up, 20 so that the lock-stitch is formed without any twist either in the shuttle-thread or the supply-thread, a result which enables the loop to be accurately positioned in the material.

I would say that I am aware that it is not 25 novel to form a lock-stitch without a twist in the shuttle-thread or supply-thread, but in so far as I am informed of the state of the art it is novel in a machine embodying a re-

ciprocating shuttle and a circular needle to secure such result by supporting a shuttle- 30 thread within the path of motion of the needle.

I therefore claim as novel and desire to secure by Letters Patent of the United States—

1. In a shoe-sewing machine, the combination with a reciprocating shuttle and a circular needle movable in substantially parallel planes, of means for actuating the shuttle and needle, and a thread-guide arranged to support the shuttle-thread within the path of motion of the needle while the shuttle is 35 40 in its retracted position, substantially as described.

2. In a shoe-sewing machine, the combination with a reciprocating shuttle, of a circular needle and its actuating mechanism, 45 and a shuttle-race provided with a thread-guide arranged to support the shuttle-thread within the path of motion of the needle while the shuttle is in its retracted position, substantially as described. 50

In testimony whereof I affix my signature in presence of two witnesses.

WILLIAM H. CURRIER.
